UNITED STATES PATENT OFFICE.

CHARLES P. BRADLEY, OF PEMBERTON, NEW JERSEY.

STREET AND STATION ANNUNCIATOR.

1,117,317.

Specification of Letters Patent. Patented Nov. 17, 1914.

Application filed August 10, 1914. Serial No. 856,052.

To all whom it may concern:

Be it known that I, CHARLES P. BRADLEY, a citizen of the United States, residing at Pemberton, in the county of Burlington and 5 State of New Jersey, have invented a new and useful Street and Station Annunciator, of which the following is a specification.

The device forming the subject matter of this application is adapted to be employed 10 upon street railways cars and other vehicles, for the purpose of disclosing to the passengers, the name of the street or station which the vehicle is approaching.

One object of the present invention is to 15 provide novel means for operatively connecting the drums, which carry the inscribed web, with the actuating member.

Another object of the invention is to provide novel stop mechanism for limiting the 20 movement of the flexible element or web which is assembled with the drums.

Another object of the invention is to provide novel means whereby the direction of movement of the web may be reversed, as is 25 necessary when the car or vehicle runs back over a route previously traversed.

It is within the scope of the invention to 30 improve generally and to enhance the utility of devices of that type to which the present invention appertains.

With the above and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed without deviating from the spirit of the invention.

In the drawings:—Figure 1 shows the invention in section; Fig. 2 is a section taken at right angles to the showing of Fig. 1, parts being broken away; Fig. 3 is a cross section on the line 3—3 of Fig. 1; Fig. 4 is a fragmental sectional detail illustrating the operative connection between the gear train and one drum; Fig. 5 is a fragmental elevation showing a modified form of the invention.

In carrying out the invention there is provided a box-like casing 1 constituting a support for the various movable elements of the device, the casing 1 being equipped at one 55 side with a transparent plate 2. Mounted in the casing 1 and extended transversely

thereof are shafts 3 upon which are mounted drums 4 to which are secured ratchet wheels 5 adapted to be actuated by pawls 6 pivoted to pinions 7 journaled on the shafts 60 3, the pinions 7 meshing into gear wheels 8 carried by stub-shafts 9 supported on the casing 1.

Located between the gear wheels 8 is an actuating member 10 in the form of a rod. 65 The actuating member 10 is mounted to right line sliding movement in the casing 1 and is mounted to rotate therein. The actuating member 10 is provided with a rack 11. When the actuating member 10 is 70 rotated on its axis, the rack 11 may be made to mesh into either of the gear wheels 8 and when the actuating member 10 is moved in the direction of its length, that gear wheel 8 with which the rack 11 meshes, and the 75 corresponding drum 4, will be rotated, the gear wheel 8 meshing into the pinion 7 and the pinion 7 driving the drum 4 through the instrumentality of the pawl 6 and the ratchet wheel 5. A ring or the like indicated at 12, is secured to one end of the actuating member 10. This ring 12 may be connected with a cord or the like (not shown) 80 so that the structure may be operated from a distant point. The ring 12 coacts with the 85 casing 1, as will be evident from Fig. 1, to limit the movement of the actuating member 10 under the action of a retractile spring 25, one end of which is secured as shown at 26 to the casing 1, and the other end of which 90 is secured to a washer 27 in which the actuating member 10 is journaled, there being a collar 28 on the actuating member 10 against which the washer 27 bears. At one end, the actuating member 10 is provided with a 95 handle 14 whereby the actuating member 10 may be rotated on its axis, to cause the rack 11 to mesh with either of the gear wheels 8.

A means is provided whereby the actuating member 10 will be prevented from rotating, saving when forcibly turned through the medium of the handle 14. With this end in view, a support 15 in the form of a block or the like is attached to the casing 1 and carries a stiff spring tongue 16. As indicated at 38, opposed sides of the actuating member 10 are flattened to coact with the free portion of the tongue 16. The function of the spring tongue 16 is to prevent the rack 11 from moving out of mesh with the gear wheel 8 during the ordinary operation of the device and when the actuating member 10 is

5 moved in direction of its length. Intermediate its ends, the actuating member 10 is provided with a diamond shaped head 17, the inclined edges 18 and 19 of which constitute cams adapted to coact with a stop mechanism to be described hereinafter. The stop mechanism embodies an angular lever 190 mounted to swing on a fulcrum rod 20 supported by the casing 1. One arm 21 of the lever 190 is provided with a roller 22 adapted to traverse, at different times, the cam edges 18 and 19 of the head 17. The other arm 23 of the lever 190 terminates in an angular finger 24.

10 15 A flexible structure is terminally secured to the drums 4, the flexible structure in the present instance being in the form of a web 29 passed over idlers 30 and 31 carried by shafts 32 on the casing 1. In the web 29 at intervals are openings 33 adapted to coact with the finger 24. The flexible structure above defined need not of necessity consist of the single web 29. By Fig. 5 of the drawings one drum is shown at 34, the web 29 is shown at 35, and, extended between the drums and secured thereto is a strip 36 which may be made of flexible metal, the strip 36 having openings 37 corresponding to the openings 33. The term "flexible structure" is to be construed as meaning either the web 29, or the web 36 and the strip 37 taken together. The web 29 is inscribed at intervals with the names of stations or streets as is common in the art. When the actuating member 10 is moved upwardly, referring to Fig. 1, the rack 11 actuates the gear wheel 3, the latter drives the pinion 7, the pawl 6 on the pinion 7 drives the ratchet wheel 5 and the latter imparts rotation to the drum 4. When the actuating member 10 is drawn upwardly, the spring 25 is put under tension and when the actuating member is released, the spring 25 draws the actuating member downwardly. At each upward movement of the actuating member 10, the corresponding drum 4 is rotated sufficiently and the web 33 is advanced enough so that a new inscription on the web appears opposite the plate 2. Obviously, upon the downward movement of the actuating member 10, due to the action of the spring 25, the drum should not be rotated, and for this purpose, the lost motion connection involving the pawl 6 and the ratchet wheel 5 is interposed in the gear train which operatively connects the actuating member 10 with the drum 4. Upon the return trip, the actuating member 10 is rotated through the medium of the handle 14, the actuating member turning freely in the washer 27. By this operation, the rack 11 is swung out of mesh with one gear wheel 8 and is swung into mesh with the other gear wheel. Then, when the actuating member 10 is operated in the manner hereinbefore set forth, the names

on the web 29 will appear in reverse order through the transparent plate 2.

As hereinbefore set forth, the function of the spring 16 is to prevent the actuating member 10 from rotating, saving when the same is forcibly turned through the medium of the handle 14, the rack 11, through the medium of the spring 16 being held in mesh with the proper gear wheel 8.

When the movable portions of the structure are at rest, the roller 22 on the arm 21 of the lever 190 rests, against the lateral apex of the diamond shaped head 17, the finger 24 thus being held out of engagement with the web 29. When, however, the actuating member 10 is moved upwardly, the roller 22 traverses the cam edge 19 and thus the finger 24 is lowered into contact with the web 29 and ultimately engages in one of the openings 33. In this manner, the movement of the web is stopped positively at the proper time to enable one of the inscriptions on the web to appear through the plate 2. When the actuating member 10 moves downwardly under the force of the spring 25, the cam edge 19 of the head 17 engages the roller 22 and tilts the lever 190 on its fulcrum 20, the finger 24 thus being withdrawn from one of the openings 33. When the actuating member 10 is rotated axially, to couple up the rack 11 with the other gear wheel 8, the cam edge 18 coacts with the roller 22 in the manner hereinbefore set forth. The ring 12 cooperates with the upper portion of the casing 1 and limits positively, the movement of the actuating member 10 due to the force exerted thereon by the spring 26.

Having thus described the invention, what is claimed is:

1. In a device of the class described, a rotatably mounted drum; a flexible structure secured thereto; a slidably mounted actuating member having a cam; means for operatively connecting the actuating member with the drum; a pivotally mounted stop adapted to coact with the flexible structure, the cam engaging the stop to move the same out of engagement with the flexible structure when the actuating member moves in one direction.

2. In a device of the class described, a pair of drums; a flexible structure terminally secured to the drums; an actuating train operatively connected with each drum and including a gear wheel; a rack provided with opposed cams, the rack being mounted to slide in the direction of its length and to rotate, the rack meshing into one gear wheel, the rack being movable in the direction of its length to actuate said gear wheel and the corresponding drum, and being rotatable to permit the rack to mesh into either gear wheel; a pivotally mounted stop adapted to coact with the flexi-

ble structure, the cams, respectively, engaging the stop to move the stop out of contact with the flexible structure when the rack is moved in one direction.

5 3. In a device of the class described, a pair of drums; a flexible structure terminally secured to the drums; an actuating train operatively connected with each drum and including a gear wheel; a rack provided with opposed cams and having opposed, flattened side faces, the rack being mounted to slide in the direction of its length and to rotate, the rack meshing into one gear wheel, the rack being movable in 15 the direction of its length to actuate the said gear wheel and the corresponding drum and being rotatable to cause the rack to mesh into either gear wheel; a spring adapted to coact at different times with the flattened side faces of the rack to hold the rack in mesh with the respective gear wheels; a pivotally mounted stop adapted to coact with the flexible structure, the cams engaging the stop at different times to move 25 the stop out of contact with the flexible

structure when the rack is moved in one direction.

4. In a device of the class described, a rotatably mounted drum; an actuating train operatively connected with the drum and 30 including a gear wheel; a rack bar mounted to slide in the direction of its length and meshing into the gear wheel, the rack being provided with a flattened side face and having a cam; a spring bearing against the 35 flattened side face of the rack to hold the same in mesh with the gear wheel; a flexible structure secured to the drum; a pivotally mounted stop adapted to coact with the flexible structure, the cam being adapted 40 to engage to move the stop out of contact with the flexible structure when the rack is moved in one direction.

In testimony that I claim the foregoing as my own, I have hereto affixed my signature in the presence of two witnesses.

CHARLES P. BRADLEY.
